(57) **CLAIM**

The ornamental design for a beverage container with a set of windows, as shown and described.

DESCRIPTION

FIG. 1 is a perspective view of a first embodiment of the beverage container with a set of windows;

FIG. 2 is front elevation view thereof;

FIG. 3 is rear elevation view thereof;

FIG. 4 is top elevation view thereof;

FIG. 5 is bottom elevation view thereof;

FIG. 6 is side elevation view thereof, the alternate side elevation being a mirror image thereto;

FIG. 7 is a perspective view of a second embodiment of the beverage container with a set of windows;

FIG. 8 is front elevation view thereof;

FIG. 9 is rear elevation view thereof;

FIG. 10 is top elevation view thereof;

FIG. 11 is bottom elevation view thereof; and,

FIG. 12 is side elevation view thereof, the alternate side elevation being a mirror image thereto.

The broken lines in all figures shown represent environment and form no part of the claimed design.
